COIL WINDING MACHINE

Frank Martindell, Western Springs, Ill., assignor
to Western Electric Company, Incorporated,
New York, N. Y., a corporation of New York

Application October 15, 1937, Serial No. 169,132

26 Claims. (Cl. 164—42)

This invention relates to coil winding machines, and more particularly to mechanism for introducing or injecting measured sheets of insulating material between superimposed layers of coils while they are being wound.

In the Hofstetter et al. patent, 2,030,989, granted February 18, 1936, there is disclosed a coil winding machine in which mechanism is provided for delivering measured sheets of insulating material to coils being wound for insertion between the superimposed layers of windings, the said mechanism comprising means for withdrawing and severing measured lengths of sheet material from a continuous strip thereof, and a pair of intermittently driven rollers for delivering the severed sheets to the coils. The mechanism referred to also comprises means for automatically increasing the length of successive sheets and for adjusting the position of the sheet delivery rollers to compensate for the increasing diameter of the coils being wound.

Objects of the present invention are to provide an improved, self-contained, reliable and readily adjustable sheet material handling mechanism of the general type above referred to.

In accordance with the above objects, one embodiment of the invention contemplates the provision of a self-contained sheet material handling mechanism comprising readily adjustable means for withdrawing and severing sheets of successively increasing lengths from a continuous strip of sheet material, and means, preferably in the form of spring operated rollers, adapted to first position the sheet with its forward edge in close proximity to the coils being wound and then, at the proper time, deliver the sheet to the coils for insertion between the superimposed layers of windings. Means is also provided for preventing operation of the several mechanisms except at the proper times and in the desired sequence.

Other features and advantages of the invention will be apparent from the following detailed description when read in conjunction with the accompanying drawings, in which

Fig. 1 is a plan view of a sheet material handling mechanism embodying the invention in operative association with a coil winding arbor;

Fig. 2 is an enlarged side elevational view, looking from the left side of Fig. 1;

Fig. 3 is a side view similar to Fig. 2, but with some of the parts broken away to more clearly illustrate the sheet delivery roller operating mechanisms which are shown in different positions than in Fig. 2;

Fig. 4 is an enlarged vertical sectional view taken on line 4—4 of Fig. 1;

Fig. 5 is an enlarged vertical sectional view taken on line 5—5 of Fig. 1;

Fig. 6 is an enlarged fragmentary sectional view taken on line 6—6 of Fig. 1;

Fig. 7 is an enlarged fragmentary sectional view taken on the line 7—7 of Fig. 1;

Fig. 8 is a sectional view similar to Fig. 7 with some of the parts shown in different positions than in Fig. 7;

Fig. 9 is a fragmentary sectional view taken on line 9—9 of Fig. 4, but showing the clutch in the normal or disengaged position;

Fig. 10 is an enlarged detail section taken on line 10—10 of Fig. 4;

Fig. 11 is an enlarged detail section taken on line 11—11 of Fig. 1;

Fig. 12 is a detail section taken on line 12—12 of Fig. 11, and

Fig. 13 is a schematic illustration of the electrical operating and control circuits.

It will be noted that in Figs. 1, 2, 4 to 8, inclusive, and 10 to 12, inclusive, the several operating parts are shown in the positions which they assume at some intermediate point during an operating cycle of the mechanism, while in Figs. 3, 9 and 13, the parts illustrated are shown in their "at rest" positions, i. e., in the positions which they assume during the interval between successive operating cycles of the mechanism.

Referring to the drawings, and first to Fig. 1 thereof, it will be seen that the mechanism is shown associated with a coil winding machine arbor or mandrel 20 which is mounted in the usual rotatable head and tail stocks 21 and 22, respectively. The head stock is provided with the usual hand wheel 23 and is adapted to be driven by any suitable power means (not shown). The winding arbor is preferably constructed and/or provided with suitable means (not shown) for attaching thereto at spaced intervals the ends of a plurality of supply wires 24 drawn from a corresponding number of supply spools (not shown). It will be understood that upon rotation of the winding arbor, the wires are drawn from the respective supplies and wound on separated zones of the arbor, suitable means being provided for distributing the wires evenly on the arbor and in superimposed layers.

It is believed that the above brief reference to the winding arbor and wire distributing means is sufficient to a complete understanding of the present invention, which pertains primarily to mechanism for withdrawing and severing pro-

20

50

55

gressively increasing lengths of sheet material from a continuous strip thereof and for delivering the severed sheets to coils while being wound for insertion between the superimposed layers of windings.

The illustrated embodiment of the invention comprises a supporting frame in the form of a base plate 25 (Figs. 2 to 5, inclusive) adapted to rest on and be attached to a suitable table or bench top 26. The base plate is formed at its rear end with two spaced apart upstanding arms or brackets 27 and 28. Pivoted at its rear end at 29 between the upper ends of the brackets 27 and 28 is an angularly adjustable frame 31 comprising spaced apart side plates 32, 32, rigidly interconnected at their rear ends by a horizontal spacer bar 34 and at their forward ends by a spacer bar 35. At its forward end, the pivoted frame 31 is supported by a carriage 37 adapted to ride on a pair of cam tracks 38-38 for a purpose hereinafter described.

Referring to Figs. 2, 5, 7 and 8, it will be seen that the forward ends of the side plates 32 are disposed adjacent the winding arbor 20 and rotatably support a lower sheet delivery roller 40. This roller is mounted on a horizontal shaft 41 rotatably journaled at its ends in bearings 43, 43 mounted in vertical slots 44, 44 in the forward ends of the side plates. For cooperating with the lower roller 40, an upper roller 46 is mounted on a horizontal shaft 47 rotatably journaled at its ends in bearing blocks 48, 48 which are pivotally suspended by means of pins 49, 49 from the forward ends of horizontal bars 50, 50. The bars 50 are pivoted at their rear ends at 51, 51 to vertical plates 52, 52 secured to the rear ends of the side plates 32. The forward end of each of the bars 50 is yieldably pressed downwardly by a vertical coil spring 54 having its upper end fastened to the bar and its lower end attached to the adjacent side plate 32.

The bearing blocks 48 which carry the upper roller 46 are vertically slidable in the vertical slots 44 of the side plates, and the downward pull of the springs 54 presses the upper roller downwardly against the lower roller 40. The vertical slots permit raising or separating the upper roller from the lower roller to facilitate the insertion of the forward edge of the material between the rollers and also to facilitate withdrawal of the severed sheet from between the rollers by the coils being wound after the forward edge of the sheet has been grasped by the wires being wound.

Upon the upper roller shaft 47, near each end thereof, there is mounted a cam 53 (Figs. 4 and 10) and below each of these cams a cooperating collar 55 is fixed to the lower roller shaft 41. The cams have high portions 54 which cooperate with the collars to separate the upper roller from the lower roller as soon as the sheet has been delivered to and grasped by the wires being wound into coils. Each of the cams has a projection 58 for cooperating with collar 55 to prevent counter-clockwise rotation of the cam beyond roller separating position. The cams are loose on the upper roller shaft and have a pin and slot connection 56 therewith, which permits a limited relative rotary movement of the upper roller with respect to the cams, for a purpose hereinafter described.

In accordance with a feature of the present invention, simple and reliable mechanism is provided for intermittently rotating the rollers in timed relation with the coil winding operation, whereby the sheet is at the proper time delivered to the coils being wound and inserted between

successive layers of windings. In the illustrated embodiment of the invention, the upper roller 46 is adapted to be rotated by an endwise movable rack bar 57 (Figs. 2 and 3) intermeshing with a pinion 58 on one end of the upper roller shaft 47. The bearing block 48 at this end of the roller shaft carries a flanged guide roller 60 under which the rack bar 57 is adapted to slide and thereby be held in driving engagement with the pinion. Lateral displacement of the rack bar is prevented by the guide roller flange which slidably holds the rack bar against the outer surface of the bearing block, as shown in Fig. 4. At its rear end, the rack bar is slidably guided in a slot 62 of a bifurcated guide and stop block 63 secured to and projecting upwardly from the upstanding bracket 27 of the base plate.

An angle plate 65 is attached to the outer side of the rack bar and a coil spring 66 has one end fastened to the angle plate and the other end attached to frame bracket 27, so that the spring serves to move the rack bar rearwardly. A transverse stop pin 68 in the rack bar is adapted to engage the front side of stop block 63 to limit rearward movement of the rack bar. During each cycle of its operation, as hereinafter described, the rack bar is held in an intermediate position by the engagement of a shoulder 70 on the tail end of the rack bar with the front side of block 63. The tail end of the rack bar is normally held down by its own weight and also by the downwardly inclined spring 66, so that when the rack bar is shifted rearwardly from its foremost position (Fig. 2) the shoulder 70 is urged into engagement with stop block 63, thereby stopping and holding the rack bar in the intermediate position (Fig. 3).

An electro-magnet or solenoid 72 is provided which is energized at the proper time to elevate the tail end of the rack bar sufficiently to release the stop shoulder 70 from stop block 63 and thereby permit spring 66 to further shift the rack bar rearwardly until stop pin 68 engages the front side of the stop block. The solenoid is mounted on one of the side plates 32 of pivoted frame 31 and comprises a plunger 73 to which a pair of spaced links 74, 74 are pivotally connected. The links loosely straddle the rack bar and are connected at their bottom ends by a spacer pin 75 which carries a roller adapted to engage the under side of the rack bar and lift it when the solenoid is energized.

The rack bar is intermittently moved forwardly, against the opposing force of spring 66, by an oscillatory angular arm 77. This arm is pivoted at its lower end on a shaft 76 journaled in brackets 78, 78 depending from the base plate 25. At its upper end, the pivoted arm 77 carries an adjustable striker screw 79 adapted to engage the rear face of angle plate 65 on the rack bar. The pivoted arm is swung forwardly by a crank arm 80 on a cam shaft 81, the crank arm carrying a roller 82 for rolling engagement with the pivoted arm. The pivoted arm is returned by a coil spring 84 and its return movement is limited by the engagement of an adjustable stop screw 85 on the pivoted arm with a stop lug 86 on adjacent bracket 78.

The cam shaft 81 is rotatably mounted in upstanding bearings 87 on the base plate 25 and is intermittently driven from a continuously rotating sprocket wheel 88 (Figs. 4 and 9) which is free to rotate on the cam shaft. The sprocket wheel is formed with a series of driving clutch teeth 89. Also mounted on the cam shaft is a

driven clutch member 98 having a series of clutch teeth 91 adapted to inter-engage with the driving clutch teeth of the sprocket wheel. The driven clutch member is slideable on the shaft into and out of driving engagement with the driving sprocket wheel; and the shaft is constrained to rotate with the driven clutch member since the latter has a sliding tongue and groove connection 93 with a sleeve 94 fixed to the shaft, as shown in Fig. 9. An adjustable spring 95 normally tends to shift the driven clutch member into driving engagement with the driving sprocket wheel, and a roller 96 on the end of a plunger 97 normally engages a high portion 92 of a shoulder cam surface 98 on the driven clutch member to hold the latter in the disengaged position. The plunger is slideable in a bearing 99 on base plate 25 and is held in the projected or holding position by a spring 100. At the proper time, the plunger is retracted or withdrawn by a solenoid or electro-magnet 101 mounted on an upstanding portion 102 of the base plate. Upon withdrawal of the plunger, spring 95 forces clutch member 98 into driving engagement with rotating sprocket wheel 88, whereupon cam shaft 81 begins to rotate. As soon as a stop lug 104 on the driven clutch member passes the roller 96 on the end of the plunger and upon de-energization of solenoid 101, the plunger is spring returned to the projected position in which the roller rides along the low portion of cam surface 98. Upon rotation of the cam shaft through one complete revolution, the high portion 92 of the cam surface approaches and finally engages roller 96, thereby shifting the driven clutch member out of engagement with the rotating sprocket wheel, whereupon stop lug 104 positively prevents further rotation of the cam shaft. An annular disk 106 (Fig. 9) is mounted on the cam shaft between the driving sprocket wheel and the driven clutch member, and is slidably keyed to the latter by a slot and tongue connection 107. A spring 108 presses the disk 106 toward the driving sprocket wheel and a leather washer 109 is interposed between the disk and the driving sprocket wheel. This, in effect, provides a friction drive between the sprocket wheel and the driven clutch member, which serves to insure that the one-revolution cam shaft 81 will at all times come to rest at the same position in which the stop lug 104 engages the underside of the plunger roller 96.

Means is provided for intermittently withdrawing a continuous strip of sheet material from a supply roll thereof and inserting the forward edge of the strip between the sheet delivery rollers 40 and 46. This means comprises a reciprocatory horizontal plate or table 111 disposed between and rigidly attached to a pair of spaced upstanding members 112, 112. Each of the members 112 has two spaced apart stub shafts 114 and 115 projecting horizontally from the outer surface thereof, the stub shafts 114 being mounted near the rear ends of rearwardly extending tail portions 117, 117 of the members 112. Rollers 116, 116, mounted on the stub shafts, are adapted to ride in horizontal slots 118, 118 in the side plates 32 of pivoted frame 31. The construction is such that the spaced members 112 together with the horizontal plate or table 111 are movable toward and away from the sheet delivery rollers.

The stub shafts 115 are longer than the stub shafts 114 and each stub shaft 115 carries a sec-

ond roller 120. Each of the rollers 120 is straddled by a bifurcated upper end of an oscillatory arm 122 and at their lower ends, the arms 122 are fixed to the rotatable shaft 76. By swinging the arms 122 forwardly the table 111 is moved forwardly toward the sheet delivery rollers and by swinging the arms rearwardly the table is moved rearwardly away from the sheet delivery rollers. The oscillatory arms are swung forwardly by two crank arms on cam shaft 81. One of these crank arms, 80, has already been referred to and, as shown in Fig. 4, its roller 82 is of sufficient length to engage and operate the roller operating arm 11 as well as the adjacent table operating arm 122. The other crank arm, 124, carries a roller 126 for engaging and operating the other table operating arm 122. A pair of torsion springs 126, 126 on shaft 76 serve to swing the arms 122 rearwardly to thereby move the table 111 rearwardly away from the sheet delivery rollers. Rearward movement of the table is limited by stops 125, 125 adjustably mounted on the carriage 31.

A clamping bar 128 (Figs. 7 and 8) extends across the top of the paper supporting table 111 and is attached at each end to the forward portion of a substantially horizontal supporting arm 129. The arms 129 are pivoted at their rear ends on studs 130, 130 projecting inwardly from the tail portions 117 of the table supporting members 112. Thus, the clamp bar 128 is vertically movable toward and away from the upper surface of table 111. A sponge rubber strip 132 is provided on the underside of the clamp bar for yieldably clamping the strip material to the table.

The clamp bar is normally held in a raised or open position by a pair of leaf springs 133, one at each end of the clamp bar. Each of the table supporting members 112 has an overhanging bearing 134 attached to its upper end and each of the bearings 134 has an inwardly projecting stud 135 which pivotally supports a right angle lever 136. The lever comprises a downwardly projecting arm 138 and a forwardly projecting arm 139. A latch member 140 is adjustably fixed to the downwardly projecting arm 138 of each of the angle levers, so that when the angle levers are swung from the position shown in Fig. 7 to the position shown in Fig. 8, the latch members press arms 129 and clamp bar 128 downwardly, thereby causing the sponge rubber strip 132 to firmly clamp the strip material to table 111. Each of the bearings 134 has a second inwardly projecting stud 142 at its rear end and a latch actuating arm 143 is pivotally suspended from each of the studs 142. At their lower ends the pivotal latch actuators 143 carry rollers 145 adapted to engage the rear edges of the angle lever arms 138, when the latch actuators are moved counterclockwise (Fig. 7), and thereby swing the angle levers together with the latch members 140 from the release position (Fig. 7) to the clamping position (Fig. 8). A stop pin 147 on each of the latch actuating arms 143 engages the top surface of the corresponding bearing 134, thereby normally holding the latch actuators in the position shown in Fig. 7.

The forward edge of table 111 is formed with a series of spaced forwardly projecting fingers 148, 149 and yieldably pressing against the top of these fingers are similarly spaced spring fingers 150, 150 which are attached to and project forwardly from the clamp bar 128. The sheet delivery rollers 40 and 46 are provided with spaced

- peripheral grooves 152, 152 for receiving the fingers 148 and 150 upon movement of table 111 to the forward position shown in Figs. 5 and 7. Each of the upper roller supporting bars 50 has a handle bar 155 attached to the upper surface of its forward end, and by means of the handle bars the upper roller 46 may be manually raised or separated from the lower roller 40. Attached to each of the handle bars 155 is a cam block 156 having an inclined cam surface 157. For each of the cams 156 there is a cooperating cam follower 158 pivotally mounted on the outer surface of the associated table supporting member 112. Stop pins 160 prevent counter-clockwise rotation of the cam followers beyond the position shown in Figs. 7 and 8, and torsion springs 161 normally tend to rotate the cam followers counter-clockwise so that they are yieldably held in position against the stop pins.
- During the forward movement of the table 111 from the position shown in Fig. 8 to the position shown in Fig. 7, the cam followers 158 slide along the inclined cam surfaces 157, thereby raising the upper roller 46 to permit insertion of the forward end of the strip material between the rollers. As the table reaches its foremost position the cam followers slide past the cams 156, whereupon the upper roller 46 is free to drop by gravity and also by the pull of the springs 54, whereby the forward end of the strip is firmly clamped between the rollers, as shown in Fig. 7. As the upper roller drops into clamping position, adjustable abutting screws 162 carried by the handle bars 155 of the upper roller supporting bars 35 strike the forwardly projecting arms 139 of the angle levers 136, whereby the latter are rotated in a clockwise direction from the position shown in Fig. 8 to the position shown in Fig. 7. This releases the clamp bar closing latches 140, thus allowing leaf springs 133 to raise clamp bar 128 out of clamping engagement with the strip material. Thus, during the return movement of table 111 from the position shown in Fig. 7 to the position shown in Fig. 8, the table and clamp bar 45 are free to slide along the continuous strip of sheet material, while the latter is prevented from shifting rearwardly with the table since the forward edge of the strip is now firmly clamped between the rollers 40 and 46. It will be obvious that during the rearward movement of the table and clamp bar, the cam followers 158 are free to rotate in a clockwise direction against the opposing force of torsion springs 161 and, therefore, are ineffective for raising the upper roller 46.
- After the table has reached the end of its rearward movement the continuous strip is severed transversely along a line anteriorly of the forward ends of gripping fingers 149 and 150, as shown in Fig. 8. The severing means comprises a pair of power operated knives 165, 165 and a cooperating relatively stationary knife bar 166, both mounted on and movable with the carriage 37 previously referred to. The knife bar 166 is attached to the forward edge of the carriage just below the reciprocating table 111, as shown in Figs. 5, 7 and 8. The knives 165 are attached to a supporting bar 168 carried at the outer ends of a pair of arcuate oscillatory arms 169, 169 (Fig. 5) which are fixed to a horizontal shaft 170 rotatably journaled in bearing brackets 171 attached to carriage 37. As shown in Fig. 4, the cutting edges of the knives 165 taper to a central point for piercing the paper to start the cutting operation. Also, the knives are made of spring steel and are slightly bowed to insure

a nice cutting fit with the cutting edge of knife bar 166.

In accordance with a feature of the present invention, the severing mechanism is operated by means of a yieldable pantograph leverage mechanism actuated by a cam 173 on cam shaft 31. This leverage mechanism is indicated generally in Figs. 1, 4 and 5 by the reference numeral 175 and comprises a cam lever 176 pivoted intermediate its ends by being attached to a horizontal shaft 177 rotatably mounted in an upstanding bearing 178 on base plate 25. A roller 179 carried at one end of cam lever 176 is confined in a cam groove 180 in the face of cam 173. The opposite end of cam lever 176 has a floating pivotal connection 181 with the lower end of an adjustable link 182. This link is pivotally connected at its upper end to one corner of a triangular plate 183. The plate 183 has a floating pivotal connection 184 with the upper ends of a pair of spaced links 185, 186, which links have their lower ends loosely pivoted on the cam lever shaft 177. The triangular plate 183 is pivotally connected at 184 to the rear ends of a pair of arms 187, 187, which arms are carried by the carriage 37 by being pivotally connected at their forward ends on the horizontal shaft 170 mounted on the carriage. The plate 183 also has a slidable pivotal connection 188 with a bifurcated end 189 of a link 190 and the opposite end of the link is pivotally connected to the free end of a lever arm 192 attached to shaft 170. A tension spring 193 normally tends to rotate lever arm 192 in a clockwise direction and the pivot pin 188, by engaging the bottom of the slot 189 in the link 190, serves as a movable stop for opposing the force of the spring.

Referring particularly to Fig. 5, it will be seen that cam groove 180 comprises a low portion 194, which, upon rotation of the cam, causes rotation 40 of cam lever 176 in a clockwise direction. The clockwise rotation of cam lever 176 is transmitted through link 182 to plate 183. The resulting clockwise rotation of plate 183 about pivot 184 shifts stop pin 188 rearwardly, thereby permitting spring 193 to rotate lever arm 192 in a clockwise direction to effect a downward severing motion of the knives 165. Thereafter, the high portion of cam groove 180 rotates cam lever 176 counter-clockwise and through link 182, plate 183 50 and link 190, the lever arm 192 is positively rotated counter-clockwise, thereby raising the knives to their original or starting positions. It will be noted that the severing movement of the knives is effected through the spring 193, which is adapted to yield and thereby prevent damage in the event that some foreign object gets into the path of the knives.

During the first portion of the downward motion of the knives, fingers 191, 191 on the knife carrying arms 169 engage shoulder cam surfaces 195, 195 of latch operating arms 143, whereby the latter are shifted to move latches 140 from the release position to the position shown in Fig. 8, 65 so that the strip material is firmly clamped between table 111 and clamp bar 128 during the severing operation.

Since, as mentioned above, the severing means is mounted on and movable with the carriage 37 70 and since the forward edge of the continuous strip is always advanced to substantially the same position between the sheet delivery rollers prior to each severing operation, it is apparent that the position of the carriage on the cam tracks 38 75

determines the length of the sheet that is severed from the continuous strip and later inserted into the coils being wound. Referring particularly to Figs. 5 and 6, it will be seen that the carriage is provided at each end with a pair of spaced rollers 196, 196 adapted to ride in track grooves 197, 197 on the inner surfaces of the pivoted frame side plates 32. Also, at each end of the carriage there is provided intermediate and below the two rollers 196 a third roller 198 for rolling contact with the cam tracks 38. Forward movement of carriage 37 is limited by the engagement of rollers 198 with adjustable stops 200 on cam tracks 38. These stops are attached to the cam tracks by a screw and slot connection 201, whereby they are adjustable lengthwise of the cam tracks to vary the starting or foremost position of the carriage 37 in accordance with the diameter of the winding arbor or first layer of windings on the arbor. The stops are adjusted so that the first severed sheet will be of a length sufficient to completely surround the first layer of windings with the desired amount of overlap.

25 The circumference of the coils being wound obviously increases with each successive layer of windings and, therefore, it is necessary to correspondingly increase the length of successive sheets of interleaving material. This is accomplished by increasing the distance between the severing knives and the sheet delivery rollers by imparting a step-by-step rearward movement to carriage 37 at or near the beginning of each layer of windings. The means for imparting this step-by-step movement to the carriage will now be described.

In the rear end portions of the pivoted frame side plates 32 there is rotatably mounted a horizontal cross shaft 205 and fixed to opposite ends of this shaft are a pair of pinions 206, 206 in driving engagement with a pair of rack bars 207, 207 attached to the underside of carriage 37. Thus, upon rotation of shaft 205 in a counter-clockwise direction (Fig. 5), the carriage is moved rearwardly on cam tracks 38 away from stops 200 and, thereafter, upon clockwise rotation of the shaft the carriage is moved forwardly. A torsion spring 208 on shaft 205 is arranged to 50 rotate the shaft in a clockwise direction and thereby return the carriage to its foremost or starting position against the stops 200. Step-by-step rotation of the shaft in a counter-clockwise direction is accomplished by means of a spring 55 friction ratchet mechanism shown in Figs. 1, 2, 11 and 12, wherein it is indicated generally by the reference numeral 210.

The ratchet mechanism above referred to is 60 illustrated in detail in Figs. 11 and 12. It comprises three sleeves 211, 212 and 213 mounted end to end on the shaft 205 between a pair of fixed collars 214, 214, and two oppositely wound spiral springs 215 and 216 surrounding and in frictional clamping engagement with the sleeves. The end sleeves 211 and 213 are loose on the shaft, while the center sleeve 212 is fixed to the shaft. The spring 215 encircles adjoining end portions of sleeves 211 and 212 and spring 216 encircles adjoining end portions of sleeves 212 and 213. The 65 springs are held in position by centrally located peripheral ribs or shoulders 218, 219 and 220 on the sleeves 211, 212 and 213, respectively. The adjacent inner ends of the springs terminate in straight depending portions 221 and 222, respec-

tively, and the outer ends of the springs are fixed to the sleeves 211 and 213, respectively. An arm 224 fixed to sleeve 213 has a bifurcated end portion 225 (Fig. 11) engaging the fixed spacer bar 24 to thereby prevent rotation of the sleeve. 5

From the above description, it will be apparent that rotation of sleeve 211 in a counter-clockwise direction (when viewed from the left of Fig. 12) will, in effect, tend to wind spring 215, thereby causing it to contract and more firmly grasp the sleeve 212 so that this sleeve together with shaft 205 is also rotated in a counter-clockwise direction. At the same time, the counter-clockwise rotation of sleeve 212 will, in effect, tend to unwind spring 216, thereby causing it to expand so as to permit free rotation of sleeve 212 with respect thereto. Likewise, when collar 211 is rotated in the opposite direction, spring 215 is expanded and spring 216 is contracted, so that the latter spring now prevents rotation of sleeve 212 and shaft 205 while spring 215 and sleeve 211 are free to turn on sleeve 212 and shaft 205, respectively. Thus, by oscillating sleeve 211, a counter-clockwise step-by-step rotary motion is 20 imparted to the shaft 205. This movement of the shaft is transmitted through pinions 206 and rack bars 207 to impart a step-by-step rearward movement to the carriage 37. 25

Referring to Figs. 2 and 3, it will be seen that the oscillatory motion of one of the table operating arms 122 is utilized for imparting an oscillatory movement to the sleeve 211. Fixed to this sleeve is a clamp 227 which rotatably carries a depending arm 228, and upon the lower end portion of this arm a connecting block 226 is threaded for adjustment lengthwise of the arm. The connecting block is pivotally connected to one end of a link 229. At its opposite end, link 229 is pivotally connected to the upper end of a vertical lever 230 which is pivoted at its lower end to an upstanding bearing 231 on base plate 25. An arcuate bar 233 has one end pivotally connected to lever 230 intermediate its ends and, at its opposite end, bar 233 has a downward bent portion 234 adapted to be engaged by a stud 235 secured to and projecting laterally from the oscillatory arm 122. The free end of bar 233 rests on the stud 235 and lateral displacement thereof is prevented by a pair of spaced guide pins 236, 236 projecting vertically from the stud, as clearly shown in Fig. 4. 40

During the final portion of the forward movement of arm 122 from the normal position shown in Fig. 3 to its foremost position shown in Fig. 2, 55 stud 235 on arm 122 engages the downwardly bent end portion 234 of bar 233, thereby shifting the bar forwardly. This motion is transmitted through lever 230, link 229 and arm 228 to effect a counter-clockwise movement of the spring 60 ratchet sleeve 211. Return movement of this sleeve is effected by a coil spring 238 having one end attached to lever 230 and its opposite end attached to the upstanding arm 27 of the base plate. The lower end of lever 230 is formed with 65 a right angle projection 240 provided with an adjustable stop screw 241 adapted to engage the base plate 25 and thereby limit the return movement of the lever, thus limiting the return movement of spring clutch sleeve 211. 70

From the above description it is believed apparent that each time the table 111 is moved forwardly to insert the forward end of the continuous strip of sheet material between the delivery rollers 46 and 46, the carriage 37 is shifted 75

rearwardly so that each sheet that is severed from the continuous strip is slightly longer than the preceding sheet to compensate for the increasing circumference of the coils being wound. 5 The extent of each rearward movement of the carriage may be varied according to the size of the wire being wound by adjusting stop screw 241 and also by adjusting connecting block 228 on threaded arm 226, the latter adjustment being 10 obtainable by simply turning the arm in block 227.

Obviously, after a "stick" of coils has been completely wound and before starting to wind another "stick" of coils, the carriage 37 is returned to its original or starting position against the stops 200 on cam tracks 38. As mentioned above, the torsion spring 208 on shaft 205 serves to return the carriage to the starting position. Normally, torsion spring 208 is overpowered by 15 the holding effect of ratchet springs 215 and 216 on sleeve 212 fixed to shaft 205. A manually operated pull rod 245 is provided for releasing the ratchet springs and thereby allowing torsion spring 208 to rotate shaft 205 in a clockwise direction (Fig. 5) and return the carriage to the starting position. At its forward end, the pull rod is slidably supported by a vertical front plate 246 and a fixed vertical guide plate 247 slidably supports the rear end of the pull rod 20 30 (Figs. 1, 2, 11 and 12). The rear end portion of the pull rod lies between the depending ends 221 of ratchet springs 215 and 216 and is provided with a transverse pin 249. When the pull rod is shifted forwardly the pin 249 engages the 35 depending ends of the ratchet springs, thereby unwinding and releasing the springs from clamping engagement with sleeve 212 and thus allowing torsion spring 208 to return the carriage to the starting position. The pull rod is returned by a spring 250, the return movement being limited 40 by the engagement of a hand knob 251 on the forward end of the rod with the front face of vertical plate 246.

In order to insure that the sheet of interleaving material will be quickly and properly grasped by the coils being wound upon being delivered thereto by the rollers 40 and 46, it is essential 45 that the position of the sheet delivery rollers with respect to the coils being wound be such that the sheet is delivered to the coils tangentially thereof and into the bight between the wound turns and the oncoming wires. Therefore, 50 for each superimposed layer of windings it is necessary that the sheet delivery rollers be elevated slightly to compensate for the increasing diameter of the coils being wound. This step-by-step upward movement of the sheet delivery rollers is preferably obtained by having the carriage supporting upper edges of cam tracks 38 55 upwardly inclined from front to rear, as shown in Fig. 5, so that with each rearward movement of the carriage the forward end of the pivoted frame and the sheet delivery rollers carried thereby are elevated sufficiently to compensate for the 60 increasing diameter of the coils being wound.

Means is provided for adjusting the initial or starting position of the sheet delivery rollers according to the diameter of the winding arbor or first layer of windings. This means is best 65 shown in Figs. 4 and 5. The forward ends of cam tracks 38 are rigidly attached to opposite ends of a horizontal spacer bar 252. This spacer bar rests on top of bearings 253, 253 projecting forwardly from the upper corners of the vertical 70 front plate 246 so that this plate, in effect, sup-

ports the forward ends of the cam tracks. An inverted J-clamp 255 serves to clamp the spacer bar 252 to the vertical plate 246. The plate is mounted for vertical movement and is guided by two vertical posts 257, 257 which slidably fit the 5 bearings 253 and similar bearings 258, 258 at the lower corners of the plate. A vertical screw 260 (Figs. 4 and 5) has a threaded connection with a centrally located bearing 261 on plate 246. Endwise movement of the screw is prevented by a lug 10 263 fixed to the base plate and interengaging a grooved collar 264 on the lower end of the screw. At its upper end the screw is provided with a knurled knob 265 for manually turning the screw. The vertical plate is provided with a slot 15 266 to accommodate knob 265. It will be apparent that rotation of the screw in one direction will elevate the vertical plate 246 and with it the forward ends of cam tracks 38, thereby elevating the sheet delivery rollers. In a similar manner, 20 rotation of the screw in the opposite direction will lower the sheet delivery rollers.

In Figs. 2 and 5 there is shown a supply roll 267 containing a continuous strip 270 of paper or other suitable interleaving material. The supply roll may be rotatably mounted in any suitable manner, preferably underneath the rear edge of the bench top 26. The free end of the continuous strip is drawn from the supply roll upwardly and around a guide roller 268 and inserted between table 111 and clamp bar 128 with the forward edge of the strip projecting slightly beyond the forward ends of the gripping fingers 149 and 150, as shown in Fig. 8.

A preferred electrical control circuit arrangement for the mechanism is illustrated schematically in Fig. 13. The arrangement comprises a pair of normally open switches 280, 280 which are conveniently mounted in spaced apart relation so that one or the other is closed by an 40 abutment 281 on the usual wire guide traverse bar 282 at the end of each layer of windings. Either of the switches 280, when closed, connects one side 284 of an electrical current supply to one terminal of a service receptacle or socket 45 285 through a pair of normally closed contacts 286 and a manually operable main control switch 287. The other terminal of socket 285 is connected directly to the other side 288 of the current supply. The energizing windings of clutch 50 operating solenoid 101 and sheet delivery roller trip solenoid 72 are connected to a plug 289 which is removably connectable to socket 285. A switch 292 is connected in the energizing circuit of trip solenoid 72 and this switch is controlled by a 55 cam 294 on cam shaft 81. The cam is arranged to close switch 292 only when the cam shaft is in the "at rest" position shown in Fig. 13. In other words, upon rotation of the cam shaft the contacts of switch 292 immediately spring open 60 and remain open until the cam shaft completes one revolution and again arrives at the "at rest" position. This prevents more than one operation of trip solenoid 72 for each cycle of operation of the sheet material feeding mechanism. 65

The socket and plug connection above referred to serves as a convenient means for readily disconnecting the control solenoids 72 and 101 of the sheet material feeding mechanism from the current supply lines at will. A manually operable normally open switch 296 is provided for operating the sheet material feeding mechanism at will and independently of the traverse bar operated switches 280.

In coil winding machines of the general type 75

herein referred to, it is customary to employ an adjustable stop counter adapted, upon the completion of a predetermined number of turns or layers of windings, to close a normally open switch and thereby energize a stop solenoid for effecting the stopping of the winding arbor. Such an arrangement is schematically illustrated in Fig. 13, wherein a counter operated normally open switch 298 controls a stop solenoid 299. The stop solenoid, when energized, opens the normally closed contacts 286, thereby interrupting the current supply to the control and operating solenoids 72 and 101 of the sheet material feeding mechanism, except through the manually operable normally open switch 296. The current supply to these solenoids is, of course, also interrupted by main control switch 281, when open.

The operation of sheet material feeding mechanism is, briefly, as follows:

20 When the mechanism is inactive, the cam shaft clutch is disengaged, as shown in Fig. 9; the reciprocating table 111 is in the retracted position, as shown in Fig. 8; the delivery roller operating rack bar is either in the intermediate position, as shown in Fig. 3, or in its rearmost position; the switch closing cam 294 is in the switch closing position, as shown in Fig. 13; and manually operable switches 287 and 296 are open.

In setting up the mechanism for operation, the reciprocating table stops 125 are adjusted so that when the table is in its retracted position, the forward ends of gripping fingers 149 and 150 are positioned slightly behind the cutting edge of knife bar 166, as shown in Fig. 8. Then, by adjusting the striker screw 79 on rack bar operating arm 77, the extent of the forward movement of the rack bar is adjusted so that during the rearward movement of the rack bar from its foremost position (Fig. 2) to its intermediate position (Fig. 3) the delivery rollers are rotated sufficiently to "roll-out" or advance the continuous strip to a position in which the forward end of the strip is in close proximity to the winding arbor. Next, the carriage stops 200 are adjusted so that the first severed sheet will be of the required length, as explained above. Then, with the carriage in its foremost position against stops 200, the height of the forward ends of carriage supporting tracks 38 is adjusted so that the sheet delivery rollers 40 and 46 will be at the proper level. The free end of the continuous strip 270 of sheet material is then drawn from supply roll 267 and passed around guide roller 268 and between table 111 and spring gripping fingers 150. The clamp bar 128 is now pressed into clamping engagement with the strip material by manually swinging the latches 140 counter-clockwise to the position shown in Fig. 8.

The operator now momentarily closes switch 296 (Fig. 13), thereby energizing solenoids 72 and 101. If at this time the rack bar 57 is in its rearmost position with stop pin 68 in engagement with stop block 63, the operation of solenoid 72 does not cause any shifting of the rack bar, but if the rack bar is in its intermediate position, as shown in Fig. 3, then solenoid 72, upon being energized, trips the rack bar from the stop block, whereupon spring 66 shifts the rack bar rearwardly until stop pin 68 engages the stop block. By this rearward movement of the rack bar the upper roller 46 is rotated in a counter-clockwise direction, whereby any previously severed sheet that may be positioned between the two rollers is ejected and dispensed with.

75 Solenoid 101, which is energized at the same

time as solenoid 72, retracts clutch holding plunger 86, whereupon spring 85 presses driven clutch member 80 into engagement with continuously rotating driving sprocket wheel 88 and the cam shaft 81 is rotated through one complete revolution, as explained above. During the first portion of the single revolution of the cam shaft, solenoid 72 is de-energized due to the angular movement of switch closing cam 294 from its switch closing position, which permits the contacts of switch 292 to spring open. Upon further rotation of the cam shaft, crank arms 80 and 124 engage and swing forwardly the pivoted arms 77 and 122. In moving forwardly, pivoted arm 77 shifts rack bar 57 forwardly and pivoted arms 122 shift forwardly the table 111 together with the strip material which is clamped thereto.

During the forward movement of the table, upper roller 46 is separated from lower roller 40 through the cooperation of cam follower 158 with cam surface 157, thus allowing gripping fingers 149 and 150 to insert the forward end of the strip between the rollers. When the table reaches its foremost position the upper roller drops and the forward end of the strip material is thus clamped between the two rollers. As the upper roller drops into clamping engagement with the strip material, the abutting screws 162 release latches 140, thus permitting leaf springs 133 to release clamp bar 128 from clamping engagement with the strip.

Up to this time the cam shaft has been rotated through approximately 120 degrees in a clockwise direction (Figs. 2 and 3) and the crank arms 80 and 124 are now in the angular position in which crank arm 80 is shown in Fig. 2. Upon further rotation of the cam shaft in the same direction, the crank arms recede and thereupon torsion springs 126 move pivoted arms 122 together with the table 111 rearwardly against stops 125. During the rearward movement of the table, the forward end of the strip material is firmly clamped between the delivery rollers so that rearward movement of the strip material with the table is prevented.

Simultaneously with the rearward movement of the table, the pivoted arm 77 is moved rearwardly by spring 84, thereby allowing spring 66 to shift rack bar 57 rearwardly from the foremost position in which it is shown in Fig. 2 to the intermediate position in which it is stopped and held by the engagement of shoulder 70 on the rack bar with stop block 63, as shown in Fig. 3. This initial rearward movement of the rack bar to the intermediate position causes a partial revolution of upper roller 46 in a counter-clockwise direction, whereby the strip material is "rolled out" or fed forwardly by the rollers so as to position the forward edge of the strip in close proximity to the winding arbor. This feature of "rolling-out" the strip before severing the sheet therefrom is advantageous since it accomplishes the desired result of positioning the severed sheet in close proximity to the coils being wound so that only a small fraction of one revolution of the delivery rollers is necessary to inject the sheet into the coils. Thus, the sheet is very quickly and more positively inserted into the coils. A shelf 302 is provided on pivoted frame 31 for supporting the extended forward end of the strip in readiness to be injected into the coils.

As mentioned above, the amount of "roll-out" is determined by the extent of the rearward movement of the rack bar when shifted from its

foremost position to its intermediate position, which may be varied by adjusting the striker screw 78 on rack actuating arm 71. Obviously, the roller separating cams 53 (Fig. 10) are so 5 angularly positioned with respect to the upper roller that sufficient rotary motion of the upper roller, to obtain the desired amount of "roll-out" and subsequently inject the sheet into the coils, is permitted before high portions 54 of the cams 10 are rendered effective for separating the rollers. With the parts proportioned and adjusted as illustrated, the amount of "roll-out" will be approximately as illustrated by the dotted lines 300 in Fig. 7, which corresponds to a counter-clockwise rotation of the upper roller through approximately 120 degrees. In Fig. 10, the roller separating cam is shown in the angular position it assumes with respect to the upper roller shaft when the roller actuating rack bar is in its foremost position. It will be seen that the roller separating cam may be rotated counter-clockwise through approximately 45 degrees before the high portion 54 of the cam is rendered effective for separating the rollers. It will be seen, also, 15 that the pin and slot connection 56 permits counter-clockwise rotation of the upper roller through approximately 130 degrees without rotating the cam. Thus, the upper roller may be rotated counter-clockwise through a total of approximately 175 degrees before the cam is rendered effective for separating the rollers, which is just sufficient for the amount of "roll-out" illustrated and for injecting the sheet into the coils. Upon increasing the amount of "roll-out" 20 without changing the distance between the rollers and the winding arbor, the sheet is caused to be positioned closer to the coils being wound and, therefore, the extent of rotary motion of the rollers required to inject the sheet into the coils is correspondingly decreased, so that the referred to 175 degree rotation of the rollers before separation thereof remains sufficient. The amount of rotation of the rollers before separation thereof may be increased beyond the 175 degrees referred to, if necessary, by disengaging 25 the rack bar 57 from pinion 59 and then turning the upper roller together with the roller separating cams 53 in a clockwise direction (Fig. 10) through the number of degrees necessary to permit the additional amount of rotation of the rollers before separation thereof.

After the table 111 has been retracted to its rearmost position and the rack bar has been retracted to its intermediate position, as described 30 above, upon further rotation of cam shaft 81, cam 173 through the pantograph leverage mechanism 175 (Fig. 5) effects the operation of the knives 165 to sever the previously advanced portion of the strip from the continuous length. 35 The pantograph leverage mechanism constantly maintains a uniform operative relationship between the knives and the knife operating cam throughout the step-by-step rearward movement of the knives with carriage 37. Before being severed but while it is stationary the continuous strip is firmly clamped to table 111 by clamp bar 128, which is pressed downwardly by latches 140 actuated by arms 143 which, in turn, are actuated by the fingers 191 on the knife carrying arms 169 (Figs. 7 and 8). The severed end portion of the strip, which is in the form of a separate sheet, is now held in position between the delivery rollers ready to be injected into coils.

As explained above, the cam shaft clutch is 40 automatically disengaged and the cam shaft is

brought to rest immediately upon the completion of exactly one revolution thereof. As the cam shaft approaches the "at-rest" position the cam 294 is returned to its initial position in which it closes the contacts of switch 292, as shown in Fig. 13, thus reconditioning the energizing circuit for solenoid 12. This completes the setting-up cycle of operation of the sheet feeding mechanism.

Assuming now that the counter has been set 10 or reset so that counter-switch 289 (Fig. 13) is open, stop solenoid 280 is deenergized and contacts 286 are closed, and further assuming that the ends of the several supply wires have been attached to the winding arbor 20, the winding operation is started by starting rotation of the arbor, and the sheet feeding mechanism is simultaneously rendered active by closing the main control switch 287. Thereafter, upon the completion of each layer of windings, abutment 281 on the reciprocating traverse bar 282 will close one or the other of the two switches 280. The closing of either of these switches, while switch 287 and contacts 286 are closed, establishes energizing circuits for the solenoids 12 and 101, whereupon the sheet feeding mechanism is operated through one, and only one, complete cycle of operation. Each operating cycle will be substantially the same as the above described "setting-up" cycle, and it will be apparent that during each operating cycle, with the exception of the "setting-up" cycle, the delivery rollers will deliver to the coils the sheet which was inserted between the rollers, "rolled-out" and severed from the continuous strip during the preceding operating cycle. It will be apparent, also, that during each operating cycle the continuous strip is fed forwardly, inserted between the delivery rollers, "rolled-out" and then severed, as described above, so that at the end of each operating cycle a newly severed sheet is left positioned between the delivery rollers for delivery into the coils immediately at the beginning of the next succeeding operating cycle. It will be obvious, also, that during each operating cycle the carriage 37 is shifted rearwardly on cam tracks 38 by the mechanism comprising rack bars 207, pinions 206, shaft 205, the spring friction ratchet 210 and the ratchet actuating levers and linkage 228 to 234, inclusive, which is operated by one 50 of the table operating arms 122, as illustrated in Figs. 2 and 3 and hereinbefore fully described.

Since the severing mechanism comprising the oscillatory knives 165 and cooperating knife bar 166 are carried by the carriage 37 and therefore 55 are shifted rearwardly with the carriage during each operating cycle, it follows that during each operating cycle the sheet that is severed from the continuous strip is slightly longer than the sheet that was severed during the preceding operating cycle. Thus, the sheets delivered to the coils being wound will be of successively increasing length to compensate for the increasing circumference of the coils with each superimposed layer of windings. As explained above, 60 the extent to which the length of each sheet is increased over the preceding sheet may be varied, according to the gauge of the wires being wound, by adjusting the effective length of spring ratchet operating arm 228 and also by adjusting the 70 stop screw 241 which determines the extent of the oscillatory movement of arm 228.

The carriage supporting upper edges of cam tracks 38 are upwardly inclined from front to rear, as mentioned above, and the degree of inclina- 75

tion is such that upon shifting of the carriage rearwardly to increase the length of successive sheets as the coils build up on the arbor, the delivery rollers and shelf 382 are correspondingly elevated to compensate for the increasing diameter of the coils.

Upon the completion of the winding of a "stick" of coils, switch 288 (Fig. 13) is closed by the counter, whereby stop solenoid 289 is energized and thus caused to stop the winding arbor and effect the opening of contacts 288. The opening of contacts 288 renders the sheet feeding mechanism inactive. To insure that this mechanism will remain inactive until the winding of a fresh "stick" of coils has been started, switch 287 may be opened. Before starting the winding of a fresh "stick" of coils, the carriage 37 is spring returned to its starting position against stops 288 by pulling out pull rod 245, as explained above. Then switch 288 is again momentarily closed, whereby the above described "setting-up" cycle is repeated. The counter is then again reset after which the winding operation is started and the sheet feeding mechanism is simultaneously rendered active by closing the switch 287, as previously described. As the winding of the coils proceeds, the sheet feeding mechanism is operated automatically at the completion of each layer of windings to deliver a previously severed sheet to the coils for insertion between the superimposed layers of windings, as described above.

It is to be understood that the invention is not limited to the embodiment thereof herein illustrated and described except insofar as is defined by the appended claims.

What is claimed is:

1. In a sheet material handling mechanism, a sheet delivery roller, reciprocatory means for rotating the roller, a spring for moving the reciprocatory means in one direction to effect a sheet delivering operation of said roller, stop means for opposing the spring, and electro-magnetic means for rendering said stop means ineffective.
2. In a sheet material handling mechanism, a sheet delivery roller, a reciprocatory driving member for rotating said roller, a spring directly connected to the reciprocatory driving member for moving said driving member in one direction to effect a sheet delivering operation of said roller, stop means for opposing the spring, means for rendering said stop means ineffective, and means for moving said driving member in the opposite direction.
3. In a sheet material feeding mechanism, a sheet feeding roller, a reciprocatory driving member for rotating said roller, a spring for moving said driving member in one direction to effect a sheet feeding operation of said roller, stop means for limiting the movement of the roller in said direction, a second stop means for holding said driving member in an intermediate position against the opposing force of said spring, means for releasing the second stop means, and means for moving the driving member in the opposite direction to tension the spring.

4. In a sheet material handling mechanism, means for intermittently advancing a continuous strip of sheet material, a sheet severing means mounted for movement longitudinally of the strip, and means comprising a yieldable pantograph leverage mechanism for operating said severing means.

5. In a sheet material handling mechanism, means for intermittently advancing a continu-

ous strip of sheet material, means intermittently operable for severing an end portion of the strip, means for shifting the severing means longitudinally of the continuous strip to vary the lengths of the severed portions, operating means for said severing means, and a pantograph leverage mechanism for operatively connecting said operating means to said severing means.

6. In a sheet material handling mechanism, means for intermittently advancing a continuous strip of sheet material, means intermittently operable for severing an end portion of the strip, and means comprising a spring friction ratchet mechanism for intermittently shifting said severing means longitudinally of the continuous strip to vary the lengths of the severed portions.

7. In a sheet material handling mechanism, means for intermittently advancing a continuous strip of sheet material, a carriage movable longitudinally of the strip, means mounted on the carriage and intermittently operable for severing an end portion of the strip, means comprising a shaft geared to said carriage for moving the carriage longitudinally of the strip, and a spring friction ratchet mechanism for imparting a step-by-step rotary motion to said shaft.

8. In a sheet material handling mechanism, means for intermittently advancing a continuous strip of sheet material, actuating means for said strip advancing means, a carriage movable longitudinally of the strip, means mounted on the carriage for severing an end portion from the strip after each operation of the strip advancing means, means for moving the carriage comprising a shaft geared to the carriage, a spring friction ratchet mechanism for imparting a step-by-step rotary motion to said shaft, and means operated by said actuating means for operating said ratchet mechanism.

9. In a coil winding machine, coil winding means including a coil winding arbor and a reciprocatory wire guide traverse bar, and means for delivering sheet material to a coil while being wound, said last mentioned means comprising a sheet delivery roller, a reciprocatory driving member for rotating said roller, a spring for moving said driving member in one direction to effect a sheet delivering operation of said roller, stop means for limiting the extent of movement of said driving member in said direction, means for moving said driving member in the opposite direction, a second stop means for holding said driving member in an intermediate position against the opposing force of the spring, electro-magnetic means for rendering the second stop means ineffective, and means under the control of said wire guide traverse bar for controlling said electro-magnetic means.

10. In a coil winding machine, means for delivering sheet material to a coil while being wound comprising a sheet delivery roller, means for advancing sheet material into operative engagement with said delivery roller, a reciprocatory driving member for rotating the roller, means for moving the reciprocatory member in one direction, spring means for moving said member in the opposite direction to cause said roller to advance the sheet material toward the coil being wound, stop means for limiting said movement of the member under the force of said spring, and means for rendering said stop means ineffective, thereby effecting further movement of said driving member under the force of said spring to deliver the sheet material to the coil, and stop means for limiting the ex-

tent of said final movement of the roller driving member.

5 11. In a coil winding machine, means for delivering measured lengths of sheet material to a coil while being wound comprising a pair of sheet delivery rollers, means for inserting between said rollers an end portion of a continuous strip of sheet material, means for rotating one of said rollers to advance said end portion toward the coil being wound, stop means for interrupting the operation of said roller rotating means, means for severing the said end portion from the continuous strip, and means for releasing said stop means to allow said roller rotating means 10 to effect a further rotation of the roller to deliver the severed portion to the coil.

12. In a machine for delivering measured lengths of sheet material to a coil while being wound, a pair of sheet delivery rollers, a reciprocatory rack bar for driving said rollers, means for moving the rack bar in one direction, a spring for moving the rack bar in the opposite direction, stop means for limiting the movement of the rack bar under the force of said spring, a 20 second stop means for holding the rack bar in an intermediate position against the opposing force of said spring, and means rendered effective automatically at the completion of each layer of the coil being wound for rendering said second stop means ineffective.

13. In a machine for delivering sheet material to a coil being wound for insertion between superimposed layers of windings, sheet delivery means, means rendered effective automatically at the 35 completion of the winding of each layer of the coil for effecting a sheet delivering operation of said sheet delivery means, and means for preventing more than one sheet delivering operation of said sheet delivery means for each layer of 40 the coil.

14. In a machine for delivering sheet material to a coil being wound for insertion between superimposed layers of windings, sheet delivery means, means rendered effective automatically at the 45 completion of the winding of each layer of the coil for effecting a sheet delivering operation of said sheet delivery means, and manually operated means for effecting a sheet delivering operation of said sheet delivery means.

50 15. In a machine for delivering measured lengths of sheet material to a coil being wound for insertion between superimposed layers of windings, a pair of sheet delivery rollers, one of said rollers being mounted for movement toward and away from the other roller, means yieldably urging the movable roller toward the other roller, means for rotating one of said rollers, means rendered effective automatically at the completion of a predetermined amount of rotary motion 55 of said roller for separating the movable roller from the other roller, and means for varying the amount of the said rotary motion required to render the separating means effective.

65 16. In a machine for delivering sheet material to a coil being wound for insertion between superimposed layers of windings, a pair of sheet delivery rollers mounted for movement toward and away from each other, yieldable means normally urging the rollers toward each other, means comprising a cam coaxially mounted on one of said rollers for separating the rollers, and a connection between said cam and said roller for allowing a limited rotary motion of said roller with respect to said cam.

70 75 17. In a machine for delivering sheet material

to a coil being wound for insertion between superimposed layers of windings, a pair of sheet delivery rollers, intermittently operable means for advancing a continuous strip of sheet material and for inserting an end portion of the strip between said rollers, spring actuated means for rotating said rollers in one direction to advance the continuous strip to a position in close proximity to the coil being wound, disengageable stop means for temporarily limiting the rotation of 10 said rollers under the force of said spring actuated means, means for severing the end portion of the strip, and means rendered effective automatically at the completion of a layer of the coil for disengaging said stop means to thereby render said 15 spring actuated means effective for further rotating the rollers to deliver the severed sheet to the coil.

18. In a coil winding machine, coil winding means including a coil winding arbor and a reciprocatory wire guide traverse bar, and means for delivering sheet material to a coil while being wound on said arbor, said last mentioned means comprising a sheet delivery roller, a spring for rotating the roller to advance the sheet material 20 toward said arbor, stop means opposing the spring, and means under the control of said wire guide traverse bar for rendering said stop means ineffective.

19. In a coil winding machine, coil winding 30 means including a coil winding arbor and a reciprocatory wire guide traverse bar, and means for delivering sheet material to a coil while being wound on said arbor, said last mentioned means comprising a sheet delivery roller, reciprocatory 35 means for rotating the roller, a spring for moving the reciprocatory means in one direction to effect a sheet delivering operation of said roller, stop means opposing the spring, means under the control of said wire guide traverse bar for rendering 40 said stop means ineffective, and means for moving the reciprocatory means in the opposite direction.

20. In a sheet material feeding mechanism, a sheet feeding member, a driving element for said member, a spring for moving said driving 45 element in a direction to effect a sheet feeding operation of said member, stop means for limiting the movement of said element in said direction, a second stop means for holding said driving element in an intermediate position against the opposing force of said spring, means for releasing the second stop means, and means for moving the driving element in the opposite direction to tension the spring.

55 21. In a sheet material handling mechanism, means for intermittently advancing a continuous strip of sheet material, actuating means for said strip advancing means, means intermittently operable for severing an end portion of the strip, means comprising a spring ratchet mechanism 60 for intermittently shifting said severing means longitudinally of the continuous strip to vary the lengths of the severed portions, and means operated by said actuating means for operating said ratchet mechanism.

65 22. In a sheet material handling mechanism, a severing means, means for advancing an end portion of a continuous strip of sheet material past said severing means, means for operating said severing means to sever the advanced portion 70 from the continuous strip, and means actuated by said severing means for clamping the strip material to said advancing means prior to the severing operation.

75 23. In a sheet material handling mechanism,

means for intermittently advancing a continuous strip of sheet material, means intermittently operable for severing an end portion of the strip, and means actuated by said severing means for clamping the strip material to said advancing means prior to each severing operation.

5 24. In a sheet material handling mechanism, means comprising a reciprocatory table for intermittently advancing a continuous strip of sheet material, an intermittently operable oscillatory knife for severing an end portion of the strip, and a clamp bar actuated by movement of said knife for clamping the strip material to said table prior to each severing operation.

10 25. In a winding machine, a winding spindle, means comprising a reciprocatory member for intermittently advancing an end portion of a continuous strip of sheet material toward said spindle, means for clamping the material to said member, means for releasing said clamping means at the end of each sheet advancing movement of said member, severing means operated after each 15 return movement of said member for severing

the previously advanced end portion of the material from the continuous strip thereof, and means actuated by the operation of said severing means for operating the clamping means to clamp the strip material to the material advancing 5 member prior to each severing operation.

26. In a winding machine, a winding spindle, a pair of rollers for delivering sheet material to said spindle, one of said rollers being mounted for movement toward and away from the other 10 roller, means comprising a reciprocatory table for intermittently advancing and inserting between said rollers an end portion of a continuous strip of sheet material, means for clamping the material to said table, means on said table for 15 separating the movable roller from the other roller to permit insertion of the material between said rollers, means for thereafter moving the movable roller toward the other roller, and means movable with the movable roller for releasing the 20 clamping means during movement of said movable roller toward the other roller.

FRANK MARTINDELL.
